UNITED STATES PATENT OFFICE.

ALMON RICHARD HUSON, OF ROUND LAKE, ILLINOIS.

WASHING-MACHINE.

1,150,598.

Specification of Letters Patent. Patented Aug. 17, 1915.

Application filed January 6, 1912. Serial No. 669,812.

To all whom it may concern:

Be it known that I, ALMON RICHARD HUSON, a citizen of the United States, residing at Round Lake, in the county of Lake and State of Illinois, have invented a new and useful Washing-Machine, of which the following is a specification.

My invention relates to washing machines and has particular reference to a novel device of that character which shall be easy of 10 operation and efficient in service.

One of the objects of my invention is to provide for the accommodation of the clothing to be cleaned on the outside of the cylinder instead of on the inside. It naturally follows from this construction that there is no possibility of the clothes becoming rolled up or confined in such manner that the cleaning fluid may not have access to all parts thereof. Furthermore I have provided in 15 connection with the rotatable cylinder carrying the clothing in its periphery, a rubbing roll. I am aware that rubbing rolls are not broadly new but in my device the roll is distinguished from others in that it is given a 20 peripheral speed considerably greater than that of the cylinder. It is not enough that the rubbing roll shall have a different speed from that of the cylinder; it should have a greater speed for the following reasons: 25 The materials to be acted upon are secured at one point to the rotating cylinder and as the point of attachment passes the rubbing roll which is rotated in the same surface direction but at a greater speed, the clothes are 30 rubbed after the fashion of the well known washboard and are at the same time removed from the surface of the cylinder dropping loosely into the cleaning water below. This has the effect of thoroughly rubbing the clothes, then loosely dropping them 35 into the cleaning water after the fashion of hand-washing. This I consider to be an important advantage.

Another object is in the construction of 40 the cylinder itself. This cylinder is composed of a plurality of segments, when combined outlining a circle and each segment is formed with double walls; that is, making 45 an arc-shaped container or scoop, one side being closed and the other side open. The open side of the container is intended to be in the line of rotation of the cylinder with the result that as each segment passes 50 through the water it scoops up a quantity thereof, and, the outer wall being perfor-

rated, as the segment rises the water passes out through the perforations and through the materials secured to the cylinder.

For convenience I may prefer to provide 60 with the machine a boiler and heating means for the water therein. In this case, of course, connections will be provided between the boiler and the washing machine cylinder.

Other and further objects will appear 65 hereinafter and be particularly pointed out in the claims.

My invention will be more readily understood by reference to the accompanying drawings, wherein,

Figure 1 is an end elevation of a machine 70 constructed in accordance with my invention; Fig. 2 is a sectional plan on the line 2—2 of Fig. 1; Fig. 3 is a transverse section on the line 3—3 of Fig. 2; Fig. 4 is an enlarged fragmentary detail showing the means for fastening a clothes rod in place; 75 Fig. 5 is a section on the line 5—5 of Fig. 4, and Fig. 6 is an enlarged fragmentary detail of the cylinder head from the end opposite 80 from that shown in Fig. 4.

Referring to the drawings it will be seen 85 that I mount the device on suitable supports S, these supports carrying a container composed of a metallic lower portion u, and a non-metallic upper portion P. Within the container in suitable bearings I mount a shaft s, having a gear n' keyed thereto. This gear meshes with a pinion n, keyed or pinned to a stub-shaft, which shaft also 90 carries a large hand-wheel W, having a handle h, and a sprocket wheel K, of a size substantially equal to that of the gear n'. This sprocket is connected with a small 95 sprocket K', by means of a sprocket chain. The small sprocket is keyed to a transverse shaft f, this shaft carrying sprockets K'', which are in turn connected by sprocket chains with sprockets K''', rigid with a transverse shaft s'. This shaft s' carries a 100 rubbing roll r, later to be described.

The transverse shaft s, first mentioned, 105 carries the drum or cylinder of my device, the connection being through suitable heads c, spaced apart and rigidly held by means of cross-bolts q. In this case there are six of such cross-bolts. The segments d, of which there are three, rest at their four corners on brackets l. The segments are held against displacement by thumb nuts o threaded on 110 projecting studs seated in radial slots m, the studs being riveted or otherwise secured at

their bases to clips *a*. These clips have the added function of spacing apart the double walls at the middle portions of the segments.

- As heretofore stated, the drum sections or segments are provided with a double wall, the outer wall being corrugated if preferred and perforated at intervals. The two walls forming the segments have one side closed as at *y*, the opposite side being open, as at *z*.
- 10 The clothes rods *c* are adapted to be placed in the spaces between adjoining cylinder segments, there being preferably three of such rods. These rods are removable, one end adapted to be inserted in the recess *q'* of Fig. 6, and the other end in a slot 10, in the cylinder head *c*. The lower end of this slot terminates in a slotted disk *d'*, which disk is rotatable by means of a thumb nut *b'* journaled in a plate *b''* riveted to the bracket *l*.
- 15 20 After the rod is inserted in the disk in the position of Fig. 4, the disk is rotated until it assumes the position shown in Fig. 3, when the rod will be securely retained. In practice it will be understood that the materials 25 to be treated are engaged by one rod only, the free ends of the materials following the cylinder in its rotation.

The rubbing roll *r* is preferably corrugated, formed of non-metallic material and 30 is of a length substantially equal to that of the cylinder. The roll is held against the drum by means of coiled springs 11, although it may be held in place by gravity 35 action if desired. It will be noted that the roll is adapted for movement toward and from the surface of the drum as required, according to different thicknesses of material passing therebetween and that this movement is permitted because of the mounting of the bearings in an arcuate guide 12. This mounting, taken in connection with the 40 fact that the motion of the roll is caused by a sprocket chain, assures the efficient operation of the roll at all times irrespective of its 45 position. The mounting of the roll as shown is important; that is, it should be placed at approximately 30 degrees from the vertical axis of the drum. This mounting secures the advantages resulting from the increased 50 surface speed of the roll over that of the drum, in that it permits the clothes after being fulled or gathered to fall freely by gravity into the water beneath.

It will be seen by reference to the gearing 55 heretofore described that the rubbing roll is given a surface speed considerably greater than that of the cylinders, the rotation being in the same direction; that is, their peripheries are moving in the same direction at the point of contact, although in reality, the drum is moving counter-clockwise and the roll clockwise, as indicated by the arrows in Fig. 3.

I may prefer to provide water-supply 60 means, in which case brackets *x* will be se-

cured to the container, these brackets carrying a tank *t*, adapted to contain water. In this case I may provide gas or gasoline burners *b*, and a gasoline tank *g*. A conduit *i*, having a valve *J* therein, communicates with the interior of the container and provides means whereby the water heated in the tank may be supplied to the tub. An outlet *v* in the container permits the discharge of the used water.

75 It will be seen by the construction described that the drum rotating in the direction of the arrow will lift by means of the open ended segments, a quantity of water which water will be discharged from the segments through the perforated outer wall thereof. This water passing through the clothes will tend to remove impurities. As the clothes pass beneath the rubbing roll which is revolving in the same direction and 80 at a greater speed, they are thereby fulled or gathered; that is, removed from the surface of the drum, and as the last end of the material passes beneath the rubbing roll, it will fall into the water beneath and be rinsed 85 following the action secured in hand-rubbing and washing. As the cylinder revolves the clothes will again adhere closely thereto, and as they emerge from the water the liquid elevated by the segments will pass there- 90 through augmenting the previous washing action.

95 While I have shown the device as operable by hand-power, it is apparent it may be adapted for operation by water or electric 100 motor or other means.

It is obvious that many modifications may be made in the details herein described, all without departing from the spirit of my invention.

105 I claim:

1. In a washing machine, the combination of a tub, a drum rotatably mounted in said tub, said drum being made up of a plurality of double walled segments having perforated 110 outer walls, the ends and one side of said double walled segments being closed, means for attaching the clothes to be washed to the exterior of said drum and at points between said segments, whereby fluid is raised by said 115 segments and sprayed on said clothes through said perforated walls, substantially as described.

2. In a washing machine, the combination of a tub, a drum rotatably mounted in said 120 tub, means for removably securing fabrics to the surface of said drum each fabric being secured to the drum along a single longitudinal line thereof, a rubbing roll, and means for positively and independently rotating said rubbing roll at a greater surface speed than the surface speed of said drum, the co-operating surfaces of the roll and drum both moving in the same direction, 125 substantially as described.

3. In a washing machine, the combination of a container, a drum rotatably mounted in said container, means for securing fabrics to the surface of said drum, each fabric being secured to said drum along a single longitudinal line thereof, and a rubbing roll, said roll being mounted at a point removed from the vertical plane passing through the axis of the drum, and means for positively rotating said roll at a greater surface speed than the surface speed of said drum, the co-operating surfaces of said roll and drum

moving in the same direction, substantially as described.

4. A washing machine drum composed of 15 a plurality of double walled segments having perforated outer walls, the ends and one edge of said double walled segments being closed, substantially as described.

ALMON RICHARD HUSON.
